UNITED STATES PATENT OFFICE.

PETAR COLLNER, OF KEWANEE, ILLINOIS.

RAILROAD-RAIL CONNECTION.

1,176,132.

Specification of Letters Patent. Patented Mar. 21, 1916.

Application filed March 8, 1915. Serial No. 13,090.

To all whom it may concern:

Be it known that I, PETAR COLLNER, a citizen of the United States, residing at Kewanee, in the county of Henry and State of Illinois, have invented certain new and useful Improvements in Railroad-Rail Connections, of which the following is a specification, reference being had to the accompanying drawings.

10 This invention relates to certain improvements in rail fasteners; and it is an object of the invention to provide a novel and improved fastener which may be applied with convenience and facility and which serves 15 to effectively maintain the rail in operative position.

It is also an object of the invention to provide a novel and improved fastener adapted to afford a rail joint possessing a 20 maximum of strength.

The invention consists in the details of construction and in the combination and arrangement of the several parts of my improved railroad rail connection whereby 25 certain important advantages are attained and the device is rendered simpler, less expensive and otherwise more convenient and advantageous for use, all as will be hereinafter more fully set forth.

30 The novel features of the invention will be carefully defined in the appended claims.

In order that my invention may be the better understood, I will now proceed to describe the same with reference to the accompanying drawings, wherein—

Figure 1 is a view in top plan illustrating an embodiment of my invention in operative assemblage; Fig. 2 is a sectional view taken substantially on the line 2—2 of Fig. 40 1; Fig. 3 is a fragmentary view, partly in elevation and partly in section, illustrating certain details of my invention as particularly disclosed in Fig. 2; Fig. 4 is a view in elevation of the member herein employed 45 for coacting with a tie.

As disclosed in the accompanying drawings, 1—1 denote the meeting ends of rails rested upon the ties T. Coacting with the meeting ends of the rails 1 are the fish 50 plates 10 and 11, the web portion of the plate 11 being provided with the laterally disposed plate 12 integrally produced therewith and of predetermined dimensions and having depending from the rear portion 55 thereof the lug 14 terminating in the outwardly disposed lip 15 on which the head

or base portion 16 of the clamping member 17 is adapted to rest. The clamping member 17, as herein embodied, is substantially U-shape in form and has its legs 18 of 60 sufficient length to underlie the meeting ends of the rails 1 and terminate in the upstanding hook portions 19 adapted to overlie the base portion of the plate 10 in order to effectively clamp said plate 10 in operative 65 position and, as is particularly disclosed in Fig. 1, it is to be noted that the hooks 19 are disposed at the faces of the meeting rails 1—1. The base or head 16 of the clamping member 17 is provided with the outstanding 70 threaded shank 20 with which is engaged the clamping nut or bur 21 adapted to bear against the free end face of the lip 15 and the outer end face of the plate 12 so that the clamping member 17 may be 75 readily and conveniently applied in operative position and adjusted to effectively hold the plate 10 in place. The plate 12 is also provided with the upstanding rib or web 22 integrally formed therewith and 80 with the upper portion of the plate 11, as is particularly shown in Figs. 1 and 2.

The plate 12 adjacent the opposite ends and preferably at points in close proximity to the rails 1 has disposed therethrough the 85 upstanding stems 23 of the longitudinally disposed members 24 adapted to be extended within the adjacent side faces of the ties T whereby the plate 11 is held against creeping and the upper end portions of the 90 stems 23 have in threaded engagement therewith the clamping nuts 25 whereby the stems 23 may be held against displacement relative to the plate 12.

From the foregoing description, it is 95 thought to be obvious that a rail fastener constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and 105 for this reason I do not wish to be understood as limiting myself to the precise arrangement and formation of the several parts herein shown in carrying out my invention.

I claim:

1. In combination with spaced ties and a

5 rail positioned thereon, a fish plate coacting with the rail, a plate extending laterally from the fish plate and arranged intermediate the ties, vertically disposed substantially L-shape tie engaging members detachably engaged with the last named plate, the feet of said L-shape members being reversely directed and disposed longitudinally of the rail and in engagement with the adjacent ties.

10 2. In combination with spaced ties and a rail positioned thereon, a fish plate coacting with the rail, a plate extending laterally from the fish plate and arranged intermediate

15 the ties, vertically disposed substantially L-shape tie engaging members detachably engaged with and depending from the last named plate, the feet of said L-shape members being reversely directed and disposed longitudinally of the rail and in engagement with the adjacent ties.

20 In testimony whereof I hereunto affix my signature in the presence of two witnesses.

PETAR COLLNER.

Witnesses:

STEPHEN S. KENDROVIC,
PETE TUKOVICH.
